United States Patent Office.

HORACE C. WILCOX, OF WEST MERIDEN, CONNECTICUT, ASSIGNOR TO THE MERIDEN BRITANNIA COMPANY, OF THE SAME PLACE.

Design No. 2,541, dated January 1, 1867.

DESIGN FOR A CASTER-FRAME.

The Schedule referred to in these Letters Patent and making part of the same.

TO ALL WHOM IT MAY CONCERN:

Be it known that I, HORACE C. WILCOX, of West Meriden, county of New Haven, and State of Connecticut, have invented or produced a new and original Design for Caster-Frames; and I do hereby declare that the following is a full and exact description thereto, reference being had to the photographic views, in which the same letters indicate like parts.

In the accompanying views are shown a new and original design for caster-frames.

a are plain round bands as the upper member of a frame; *c* is the plain caster-spindle; *d* is a bead, as the middle member of the caster-frame; *e* is a fillet, as the lower member of the caster-frame, embellished with plain figured legs, *h*; *i* is a bracket; *k* is an intermediate ornamental support; the whole combined substantially in the manner shown and described, to produce a plain rich design for caster-frames.

What I claim, and desire to secure by Letters Patent, is—

A design for caster-frames, substantially as herein described and illustrated.

HORACE C. WILCOX. [L. S.]
